UNITED STATES PATENT OFFICE.

WILLIAM W. ROSSITER, OF NEW YORK, N. Y.

FAN FOR DISINFECTING PURPOSES.

SPECIFICATION forming part of Letters Patent No. 757,684, dated April 19, 1904.
Application filed July 21, 1903. Serial No. 166,445. (No model.)*To all whom it may concern:*

Be it known that I, WILLIAM W. ROSSITER, a citizen of the United States, residing in the borough of Brooklyn, city of New York, county of Kings, and State of New York, have invented certain new and useful Improvements in Fans for Disinfecting and other Purposes, of which the following is a specification, reference being had to the drawing accompanying and forming part of the same.

The invention which forms the subject of my present application, while it pertains, broadly, to fans of any character, relates more particularly to electric fans commonly used for ventilation and other purposes.

The object of the invention is to provide such a fan with means for loading the air-blast with vapor or minute particles of liquid. This material may be a disinfectant which it is desired to scatter throughout the room in which the fan is used or a perfume or any other liquid, according to the object sought.

To these ends the invention consists of the novel features and combinations hereinafter described, and more particularly set forth in the claims.

Referring now to the drawing, which shows a convenient embodiment of my invention, 1 indicates the standard and casing in which the 30 operating mechanism of electric fans is usually located. The armature-shaft 2, upon which the fan-blades 3 are mounted, is in the present case hollow or tubular and has at its outer end a constricted outlet-orifice 4. At the other 35 end is an inlet-orifice 5, to which is connected by a suitable coupling 6 a conduit 7. The latter extends to a point adjacent the bottom of a reservoir 8, suitably supported in the bottom of the standard. On the armature-shaft 40 is a gear-wheel 9, which by a train of gears drives a crank-shaft 10, suitably journaled in the casing. On the liquid-reservoir is an air-compressor 11, consisting in the present instance of a cylinder 12 and a piston 13, working therein. A pitman 14 connects the piston and the crank in the shaft 10. Suitable valves 15 and 16 in the piston and in the lower end of the cylinder enable the liquid in the reservoir to be put under considerable pressure by 50 the reciprocation of the piston. In order to

prevent the pressure in the reservoir from becoming too high or to maintain the same at a predetermined pressure, a safety or reducing valve 17 is provided. The spring 18, which presses the valve-head 19 into its seat, may be 55 adjusted by screwing the abutment 20 in or out.

From the foregoing the operation of the apparatus will be readily understood. The reservoir 8 having been filled through a suitable filling-orifice 21 until the same is about half full, the current is turned on, and the fan begins to rotate. At the same time the shaft 10 and its crank are revolved, thus reciprocating the piston 13 of the compressor, which forces 65 air into the space above the liquid in the reservoir. The liquid immediately ascends the conduit 7 and from there is delivered into the rotating shaft 2, from which it is discharged 70 as a fine spray at the orifice 4. The spray is immediately seized by the blast of the fan and being still further divided is carried by the currents of air from the fan into all parts of the room.

It will be seen that my invention provides a 75 convenient way of distributing vapor throughout an apartment. By this means a room—such as, for example, a public auditorium—may be constantly supplied with disinfectant, deodorizer, or perfume in a very effective 80 manner. The air in the room will be at all times thoroughly charged with the vapor or minute particles, and the purpose of the same will thus be accomplished in a more satisfactory manner than by sprinkling the floors or 85 walls with a volatile liquid or by exposing such a liquid in open receptacles. Other uses for the invention will of course be suggested according to circumstances.

The form herein shown I regard as a 90 convenient but not the only embodiment of which my invention is capable, and I therefore do not consider myself limited to the exact construction herein described; but

What I claim is—

1. In a fan or blower, in combination, a hollow shaft having an inlet-orifice, and having an outlet-orifice at the center of the rotating fan, a liquid-reservoir, a conduit connecting the inlet-orifice of the hollow shaft with the 100

reservoir, means for driving the fan, and means for discharging liquid from the reservoir through the conduit, the hollow shaft, and the outlet-orifice, as set forth.

5. 2. In a fan or blower, in combination, a hollow shaft having an inlet-orifice, and having an outlet-orifice at the center of the rotating fan, a liquid-reservoir, a conduit connecting the inlet-orifice of the hollow shaft with the reservoir, an air-compressor connected with the reservoir, means for driving the fan, and means for actuating the compressor, as set forth.
3. In a fan or blower, in combination, a hollow shaft having an inlet-orifice, and having an outlet-orifice at the center of the rotating fan, a liquid-reservoir, a conduit connecting the inlet-orifice of the hollow shaft with the

reservoir, a reciprocating air-compressor connected with the reservoir, a crank-shaft, a pitman connecting the crank-shaft and the compressor, means for driving the fan, and means for rotating the crank-shaft, as set forth.

4. In a fan or blower, in combination, a hollow shaft having an inlet-orifice, and having an outlet-orifice at the center of the rotating fan, a liquid-reservoir, a conduit connecting the inlet-orifice of the hollow shaft with the reservoir, means for driving the fan, means for compressing air above the liquid in the reservoir, and means for maintaining a constant pressure therein.

WM. W. ROSSITER.
